UNITED STATES PATENT OFFICE.

GEORGE F. LARKIN, OF NEWARK, NEW JERSEY, ASSIGNOR TO THE NEWARK HAT BLOCK COMPANY, OF SAME PLACE.

HAT-BLOCK.

SPECIFICATION forming part of Letters Patent No. 436,833, dated September 23, 1890.

Application filed January 24, 1890. Serial No. 337,956. (No model.)

To all whom it may concern:

Be it known that I, GEORGE F. LARKIN, a citizen of the United States, residing at Newark, in the county of Essex and State of New Jersey, have invented certain new and useful Improvements in Hat-Blocks Composed of Separable Pieces and Means for Uniting the Same; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The herein-described invention relates to improvements in hat-blocks which are larger at the tip than at the base; and the invention consists of a hat-block of that class which is made up of several separate pieces adapted to be removably united to each other to form the block proper.

A further object is to provide a hat-block consisting of a number of separable parts arranged around a center piece or block provided with means thereon for drawing the surrounding parts tightly together around the same and thereby forming a substantially solid hat-block.

In the accompanying two sheets of drawings, in which similar letters of reference indicate corresponding parts, Figure 1, Sheet 1, is a side elevation of the united hat-block, which is larger at the tip than at the base.

Fig. 2 represents a top view of the same, illustrating the separable pieces surrounding the center piece or block and clearly showing the mechanism for drawing and locking or holding the several parts together and thereby making a united hat-block. Fig. 3 is an enlarged horizontal section to show more clearly the arrangement of the chuck mechanism for drawing the parts together, and Fig. 4 is bottom view of the complete hat-block.

On Sheet 2, Fig. 5, is an enlarged vertical central section of the block, taken through line a in Fig. 3. Figs. 6 and 7 are perspective views of parts of the locking or holding mechanism. Fig. 8 is a perspective view of one of the jaws or dogs employed in the chuck for drawing the several parts of

the block together, and Fig. 9 is a plan view of the under side of a ring provided with a spiral employed in the chuck.

As illustrated in the above-described views, the hat-block consists of four separate portions or side pieces B, B', C, and C', arranged around the center block A in such a manner that the portion or piece B is on one side of the block A, while the piece B' is on the opposite side of said center block, and so with the portions or pieces C and C', which are also placed on opposite sides of the center block and between the side pieces B and B', respectively.

The center block A, as will be clearly seen from the drawings, is rectangular, preferably square at its lower end a , the sides of said block being wedge-shaped, as shown more clearly in Fig. 5, and the block is provided on the top thereof with a round shank or post a' . The portions B, B', C, and C' are shaped, as illustrated more clearly in Figs. 3 and 5, so that when they are closely arranged around the center block A they unite and form a complete hat-block, which is oval in cross-section, and which is larger at the tip than at its base.

The center block A has secured to its four sides, directly below and on the top of the upper rectangular surface a^2 , four guide-plates d , which are secured to the sides of said block by means of a screw or pin arranged in a perforation d^2 in a downwardly-projecting flange d' in such a manner that the lower parts of said guide-plates are countersunk into the wooden block A and the guide-arms d^3 are upon the upper surface a^2 of the center block. Said guide-arms d^3 are connected by means of a rib or bar d^4 and are provided with two upwardly-projecting posts d^5 . Working within the space formed between the guide-arms d^3 in each of said guide-plates d is a dog or jaw d^6 , hook-shaped at d^7 and provided with teeth or threads d^8 on the top and other end thereof. These dogs, arranged between the said guide-arms, are held in position therein by the rib or plate d^4 and the teeth d^8 on the inner ends, which work within a spiral e' on the lower side of a ring e , placed around and encircling the peripheral surface of the shank or post a' . Said ring e is provided with lugs e^2 or other similar means, to which a wrench may be at-

tached and by means of which said ring can be turned or rotated about said post a' on the surface a^2 . When the said ring is turned by means of the wrench, the dogs d^6 are caused 5 to move between their guide-arms d^3 , and thus adapted to be drawn inwardly toward the center of the block A or in the opposite direction away therefrom, according in which direction the ring e is turned. The operation 10 of the ring e and the dogs or jaws d^6 is similar to that of an ordinary lathe-chuck, the teeth on said dogs being caused to follow the curve of the spiral on the under side of the ring e , as will be understood. When the dogs d^6 are 15 drawn toward the center of the block A by means of said ring e , the inwardly-bent portion d^7 on each dog rides against the inner edge of the hole f^3 in the coupling device, thereby tightly forcing the flange f^2 up against 20 the under side of the dogs and also against the undersides of the guide-plates, thus causing all of said parts to be tightly wedged together, as in a vise, and preventing any possible displacement. To each of the portions 25 B, B', C, and C', respectively, are secured in any convenient manner said coupling devices f , which consist of a curved wall f' , fitting into a recessed portion in the side pieces, into which said wall is wedged and thereby held in position. Each coupling device is provided with 30 a projecting flange f^2 on the inner curved side of the wall f' , which flange is provided with a perforation f^3 therein and two upwardly-projecting guides f^4 on each side of said perforation. On opposite sides, between the outer 35 edges of the coupling device and the guides f^4 , is a V-shaped recess f^5 , the purpose of which will be described hereinafter.

In making silk hats a hat-block which is 40 larger at the tip than at the base must be used in order to produce the desired shape of the finished hat.

The operation of placing the hat-block within the hat-body is as follows: The side pieces 45 B, B', C, and C' are first placed into the bag-shaped sack or crown from which the hat is to be formed, and the center block is then forced down into the central space or opening formed by the arrangement of the side 50 pieces. When said side pieces have thus been arranged, before the insertion of the center block A, an opening is formed between said pieces, which is wedge-shaped and rectangular at the bottom to about one-half the 55 distance up the block, and above that the hole formed is circular, having been thus formed by the round coupling devices arranged on the four sides of the hole, and also by the inner surfaces of the side pieces, which 60 have been rounded out or cut away to correspond with the shape of the coupling devices. When these side pieces have been placed in position within the hat-body, the wedge-shaped block or center piece A is inserted 65 into this opening, and the four hooks d^7 on the dogs or jaws d^6 drop into the holes or perforations f^3 in the four coupling devices in

their respective side pieces. A slight turn on the ring e by means of a wrench will then cause the dogs or jaws to be drawn toward 70 their common center, and the coupling devices thus also become drawn in toward the same center, pulling the respective side pieces toward a common center, and thus forming a united and complete block with the material stretched upon the same, and which can then be drawn tight by means of the ordinary brim-forming flange in the well-known manner. The difficulty heretofore has been to 75 keep the parts of the block in position while finishing the hat without destroying the shape of the latter. By my arrangement all parts are securely held together and firmly united.

In the present construction it will readily be seen that when the hat is finished a slight 80 turn upon the collar or ring e in the opposite direction will force the dogs or jaws d^6 outwardly, and the center block can be easily removed without any detriment to the shape 85 of the hat.

To prevent any side movement of the side pieces when all the parts of the block have been 90 united, I have provided the coupling device f with the V-shaped recesses f^5 , into which fit the correspondingly V-shaped projections d^9 95 on the under sides of the plates or ends d^{10} on the guide-pieces. This also acts as a centering device, bringing the central axis of the perforation f^3 in a straight line with the longitudinal axis of the dogs or jaws d^6 . When 100 the several parts are in position and the coupling device is placed against the guides d , said upwardly-projecting guides f^4 on the upper side of the flange f^2 extend between the edges d^{11} of the plates d^{10} , thus causing 105 said plates or ends to rest upon the flange f^2 and the V-shaped projections d^9 to fit into the V-shaped recesses f^5 . Furthermore, the edges f^6 of the guides f^4 abut against the sides d^{12} of the posts d^5 , from which it is evident 110 that any side movement in any direction is prevented.

In order to prevent the dropping out of the ring e from the block in case that the latter should be turned over, the guide-plates d are 115 provided with upwardly-projecting fingers or arms d^{13} , which extend over the top surface of said ring, as illustrated in Figs. 2 and 3, but which still allow the ring to rotate beneath said fingers.

From Fig. 7 it will be seen that one end of the wall f' of the connecting or coupling device f is wider than the other, thus making the same wedge-shaped. The edges are also 120 chamfered, and, as will be seen from Fig. 5, said 125 chamfered edges of the wedge-shaped wall f' are secured within dovetailed or correspondingly-shaped grooves in the side pieces, and thus firmly held in position. Said coupling device may also be secured to the side pieces 130 by means of screws or pins.

As shown in Fig. 6, the guiding device d is formed in one piece; but I may secure the rib d^4 and the posts d^5 thereto by means of

screws, and I may entirely dispense with some of the parts, if desirable.

Having thus described my invention, what I claim is—

- 5 1. In a hat-block, in combination, a center block having a round post or shank thereon, a ring around said post provided with means for turning the same and having a spiral on one side thereof, dogs or jaws with one end of 10 which said spiral is in engagement, and side pieces arranged around said center block, provided with coupling devices, to which said dogs are attached and whereby said side pieces are caused to move toward or away 15 from said center block, for the purposes set forth.
2. In a hat-block, in combination, a center block having a post or shank thereon, a ring around said post provided with means for 20 turning the same and a spiral on one side thereof, guide-plates beneath said ring, dogs or jaws in said guide-plates, and side pieces arranged around said center block, provided with coupling devices, to which said dogs are 25 attached and whereby said side pieces are caused to move toward or away from said center block, for the purposes set forth.
3. In a hat-block, in combination, a center block provided with a shank or post, means 30 thereon for detachably securing side pieces around said center block to form a united hat-block, each of said side pieces being provided with coupling devices provided with a projecting flange having a perforation therein 35 and having V-shaped recesses which fit into V-shaped projections in guide-plates on the center block, substantially as and for the purposes set forth.
4. In a hat-block, in combination, a rect- 40 angular center block having a round post or shank thereon, a ring around said post provided with means for turning the same, guide-plates beneath said ring on the upper rectangular surface of said center block, dogs 45 or jaws in said guide-plates, and side pieces arranged around said center block, provided with coupling devices, each having a projecting flange with a perforation therein, to which said dogs are removably attached and where- 50 by said side pieces are drawn up against the center block to form a united hat-block, being larger at the tip than at the base, as and for the purposes set forth.
5. In a hat-block, in combination, a rectan- 55 gular center block having a round post or shank, a ring around said post provided with means for turning the same, guide-plates beneath said ring on the upper rectangular sur- 60 face of said center block, dogs or jaws in said guide-plates provided with teeth or projections which co-operate with a spiral on said ring, and side pieces arranged around said center block, provided with coupling devices, each having a projecting flange with a perforation 65 therein, to which said dogs are attached and whereby said side pieces are drawn up against the center block to form a united hat-block, being larger at the tip than at the base, as and for the purposes set forth.
6. In a hat-block, in combination, a rectan- 70 gular center block having a round post or shank, a ring around said post provided with means for turning the same, guide-plates beneath said ring on the upper rectangular surface of said center block, dogs or jaws in said 75 guide-plates, being hook-shaped at one end and having teeth or projections on their opposite ends which co-operate with a spiral on said ring, and side pieces arranged around said center block, provided with coupling devices, 80 each having a projecting flange with a perforation therein, to which said hooks on the dogs are attached and whereby said side pieces are drawn up against the center block to form a united hat-block, being larger at the tip 85 than at the base, as and for the purposes set forth.
7. In a hat-block, in combination, a rectan- 90 gular center block having a round post or shank, a ring around said post provided with means for turning the same, guide-plates secured to said center block beneath said ring, dogs or jaws in said guide-plates, being hook-shaped at one end and having teeth or projections on their opposite ends which co-oper- 95 ate with a spiral on said ring, a rib on said guide-plates, means to hold said ring around the post on the center block in position, side pieces arranged around said center block, provided with coupling devices, each having 100 a projecting flange with a perforation therein, to which said hooks on the dogs or jaws are attached, and V-shaped recesses in said projecting flange into which fit corresponding V-shaped projections on the under side of said 105 guide-plates on the center block, all of said parts being arranged substantially as and for the purposes set forth.
8. In a hat-block, the herein-described guide- 110 plates, consisting, essentially, of the guiding arms d^3 , connected by means of a downwardly-projecting flange d^4 , provided with posts d^5 , a rib d^6 , and V-shaped projections d^7 , as set forth.
9. The herein-described coupling device for 115 coupling the side pieces in a hat-block to a chuck on a center block, as set forth, said coupling device consisting, essentially, of a curved wall f^1 for securing the same to the side piece, the projecting flange f^2 , perforation f^3 therein, V-shaped recesses in said flange, and upwardly-projecting guides thereon, as set forth.
- In testimony that I claim the invention set forth above I have hereunto set my hand this 125 22d day of January, 1890.

GEORGE F. LARKIN.
